UNITED STATES PATENT OFFICE.

JOHN M. SINER, OF BROOKLYN, NEW YORK

GARMENT-CLASP.

No. 884,425.

Specification of Letters Patent. Patented April 14, 1908.

Application filed September 28, 1907. Serial No. 394,977.

To all whom it may concern:

Be it known that I, JOHN M. SINER, a citizen of the United States, residing at Brooklyn, in the county of Kings and State of New York, have invented certain new and useful Improvements in Garment-Clasps, of which the following is a full, clear, and exact description.

My invention relates to garter or garment clasps, particularly of that type designed to clasp or grip a stocking in a firm and substantial manner between rounded surfaces, the engagement extending over a sufficient area to preclude any injury to the fabric.

In carrying out the present invention, I aim to provide a form of clasp in which the fabric is gripped tightly throughout an extended area. In addition to this, I provide means by which the clasp is locked in use so as to be insured against any accidental release. But in securing these advantages, the general appearance of the ordinary garter clasp has not been widely departed from, and the advantages of easy clasping and unclasping manipulation are retained.

With these objects in view the invention consists in the features of construction and combination as hereinafter set forth and claimed.

In the drawings: Figure 1 is a front view or elevation of a garter clasp embodying the principles of my invention. Fig. 2 is a view of the same in unclasping or disengaged relation. Fig. 3 is a vertical sectional view of the same. Fig. 4 is a similar view in clasped or engaged relation; and Fig. 5 is a detail view of one of the parts.

Referring to the drawings in which like parts are designated by the same reference sign, 1 indicates the main frame member or backing plate, having an opening 2, at its upper end, in which the usual garter strap or similar device 3, is secured. The plate or member 1 is made quite long, corresponding to substantially the entire length of the complete clasp, and conveniently of sheet metal or resilient substance.

4 indicates a button permanently attached to the lower end of the plate or member 1. I prefer to make the part 4 of wood or similar rigid substance with a fairly soft or friction surface. The reasons by which it is possible or even advantageous to make the button 4 in this way will later more particularly appear. The form of the button 4 may be accorded to any particular re-

quirements, that shown having a rounded tapered shank 5, and an enlarged rounded head 6, being an advantageous shape for ordinary use. At a convenient distance 60 from the button 4 upon the body of the plate or member 1 there is an offset portion 7, and immediately adjacent thereto I provide integral ears 8, deflected laterally from the plate 1 into parallel relation with one 65 another, and extending forwardly in the same direction from the plate as the button 4.

9 indicate holes or perforations in the ears 8 in transverse alignment with one another, and adapted to constitute pivot bearings. 70 These pivot bearings receive a link 10 (shown particularly in Fig. 5).

The details of construction of the link 10 may be varied in practice, but I prefer the construction shown, and comprising a piece 75 of sheet metal turned over at one end to form an eye 11, and having integral lugs or extensions 12, at the other end in transverse alignment with one another and received in the pivot bearings 9. 13 indicates an offset portion 80 in the link by which the axis of the eye 11 is brought into symmetrical relation with the remainder of the outline, and certain locking functions of the link attained, as will later appear. Within the eye 11, there is received the loop, hoop, or socket member 14, the essential characteristic of which is a recess or jaw 15, of sufficient width to receive the shank 5 of the button 4. This loop or jaw member is rounded at 16, so as to swivel 90 freely in the eye 11 of the link 10. Its length is such that the rounded end surface 17 bears tightly against the shank 5 of the button when the link is directed upwardly, as particularly shown in Figs. 1 and 4. The 95 central portion is widened and has a large opening or cavity 17', considerably larger than the largest diameter of the button 4, this cavity gradually tapering or narrowing downward into the recess or jaw 15 mentioned. At its upper end, the loop or jaw member 14 is widened at 14' which provides for its easy engagement and manipulation by the fingers in use.

The metal of the clasp is enveloped and 105 protected by a fabric covering 18, which is threaded through openings 19 and 20 in the plate 1, and has its ends extending upwardly and sewed to the garter strap 3. In this way the rear surface of the garter clasp is 110 entirely covered and the metal kept from direct contact with the body of the wearer in use

The use and operation is as follows: It being desired to clasp or engage the fabric of a stocking or other garment, the loop or jaw member 14 is drawn outward until the link 10 stands outward from the plate 1, or hangs downward therefrom in the manner shown in Fig. 2. Under these circumstances, the button 4 lies opposite the widely open portion 17' of the loop or jaw member. In this position 10 the fabric of the stocking is easily engaged and pushed into a position to be clasped. If the link 10 is now swung upwardly, the loop or jaw member 17 will be drawn upwardly toward the button 4 and eventually bind tightly 15 against the same when the link 10 assumes a vertical position, as shown in Figs. 1 and 4. As the button is at this time surrounded by the fabric to be clasped, it is evident that the latter is also tightly gripped around 20 substantially half or more of the circumference of the button. It will be noted that in this action the link 10 acts as a toggle joint and secures a very considerable clamping pressure with only a very moderate force of manipulation. It is by reason of this fact that a 25 rigid button 4 is best, since a wooden or rigid button resists the clamping pressure with a more adequate force of reaction than a highly flexible button made of rubber. Not only 30 are these various features secured, but an additional locking function is obtained by the link 10. This is achieved by reason of the offset portion 7 of the plate or member 1, together with the offset part 13 of the link 10. 35 Such construction permits the link 10 swing to a point beyond the center where it is in alignment with the strain of the clasp. In this position the strain of the clamping

engagement locks or holds the link against accidental displacement so that the clasp is 40 secured against disengagement until the link is forcibly drawn outward by the application of an adequate force. In order that the clasp may operate with equal efficiency for all grades and thicknesses of fabric, it is best 45 to make the backing plate 1 of resilient material so that it can yield or buckle slightly along the portion 21, when the clamp is in use. In this way, the clamping force corresponds to the elasticity against deformation of such backing and this force is substantially the same whether the clamp is engaged on a thin or a thick fabric.

What I claim is:—

A garment clasp comprising a frame or 55 plate having a button and offset rearwardly at the middle portion of its length, a loop or jaw member to receive said button, and a rigid sheet metal link folded over at one end to form an eye in substantially the plane of 60 said link to embrace said loop or jaw member and pivoted to said frame at its other end at a point on the side of said offset portion of the frame towards said button and near the surface of said frame, said link being offset 65 at its middle portion at a point corresponding to the offset portion of said frame, whereby said link swings into a locking relation in use.

In witness whereof, I subscribe my signature, in the presence of two witnesses.

JOHN M. SINER.
